LADY'S STOCKING

Arthur L. Patterson, Sr., Albemarle, N. C., assignor to Lillian Knitting Mills Company, Albemarle, N. C., a corporation of North Carolina

Application April 17, 1952, Serial No. 19,362

Term of patent 14 years

(Cl. D47—7)

To all whom it may concern:

Be it known that I, Arthur L. Patterson, Sr., a citizen of the United States of America, residing at Albemarle, in the county of Stanly, State of North Carolina, have invented a new, original, and ornamental Design for a Lady's Stocking, of which the following is a specification, reference being had to the accompanying drawings, forming a part thereof.

I claim:

The ornamental design for a lady's stocking, substantially as shown.

ARTHUR L. PATTERSON, SR.
